UNITED STATES PATENT OFFICE.

ARTHUR BRAY, OF LEEDS, ENGLAND.

DESIGN FOR A VERTICAL INVERTED INCANDESCENT GAS-BURNER.

40,346.

Specification for Design.

Patented Nov. 9, 1909.

Application filed June 8, 1909. Serial No. 500,986. Term of patent 14 years.

To all whom it may concern:

Be it known that I, ARTHUR BRAY, a subject of the King of Great Britain and Ireland, and residing at Bagby Works, Leicester Place, Leeds, in the county of York, England, have invented a new, original, and ornamental Design for Vertical Inverted Incandescent Gas-Burners, of which the following is a specification, reference being had to the accompanying drawing, forming part thereof.

In the drawing, Figure 1. represents an elevation of the burner. Fig. 2 represents a plan view from above.

The design comprises a cylindrical portion N having a groove in its upper part, a conical portion A extending downwardly from said cylindrical portion, said conical portion

having openings A' therein, the lower part of said conical portion having an annular projection thereon, and an annular groove immediately below said projection, and a globe supporting gallery G having openings G² therein which is connected with the conical portion A by an upwardly curved portion joining the grooved portion of the conical portion, said upwardly curved portion having a slot G' therein.

I claim:—

The ornamental design for the vertical inverted incandescent gas burner as shown and described.

ARTHUR BRAY.
